CARL A. TRAVOR, OF CHICAGO, ILLINOIS, ASSIGNOR TO C. E. BARRETT & CO., OF CHICAGO, ILLINOIS, A COPARTNERSHIP CONSISTING OF CLARENCE A. BARRETT AND LEONARD A. BARRETT, TRUSTEE

SWIVELING PEN SUPPORT

Application filed May 9, 1928. Serial No. 276,236.

My invention relates to the type of desk pen stands having a holder adapted to form a sealing cap for the forward end of a fountain pen, so as to receive and position the 5 pen.

Generally speaking, my invention aims to provide a compact, inexpensive and durable pen stand embodying these characteristics:

(1) Ready rotatability of the holder with 10 respect to the base of the stand.

(2) Ready tiltability of the holder to dispose that axis of the holder at any desired inclination, or horizontally.

(3) Effective frictional latching of the 15 holder in any adjusted position.

(4) Ready relaxing of this latching to facilitate rotational movement of the holder.

(5) Compensation for inaccuracies in the 20 manufacture of various parts.

(6) Simple means for adjusting the tightness of the latching of the holder against both tilttable and rotatable movement.

(7) Single means for simultaneously making 25 both of these adjustments.

(8) A construction permitting almost all of the parts to be assembled as a unit and attached as such to the base.

Still further and also more detailed objects will appear from the following specification and from the accompanying drawings, in which 30

Fig. 1 is a side elevation of a desk stand embodying my invention, showing this as supporting a capless fountain pen in a horizontal position.

Fig. 2 is an enlarged elevation of the assembly of parts before this is attached to the base by a clamping nut, and before the pen-receiving holder is attached to the 40 pivoted holder carrier.

Fig. 3 is a still more enlarged and fragmentary vertical section taken along the line 3-3 of Fig. 1, but with the pen-receiving holder in an upright position.

Fig. 4 and Fig. 5 are sections similar to 45 a part of Fig. 3, showing two other embodiments of my invention.

In the embodiment of Figs. 1 to 3 inclusive, my pen stand includes a base 1 having 50 a vertical bore 2, which bore has its lower

portion enlarged in diameter to afford a bottom recess 3. Extending downwardly through the main bore portion 2 and into the recess 3 is the shank 4 of a supporting member in the form of a tubular fitting which 55 has a flange 5 seating on the top of the base 1. The shank 4 is threaded to receive a nut 6 housed by the recess 3 and engaging the top of the recess to cooperate with the flange 5 for clamping the post rigidly to the base. 60

The bore of the tubular fitting comprises an upper and downwardly tapering portion 7 and a cylindrical bottom portion 8, which bottom portion is larger in diameter than the lower (smaller) end of the tapering bore 65 portion, thereby affording an inner annular and radial shoulder 9 at the top of the bottom portion 8.

Socketed in the tapering bore portion 7 is the correspondingly tapered shank 10 of 70 a post which has its upper end longitudinally slotted to afford spaced upper fork arms 11, and which has a longitudinal bore 12 extending downwardly from the space between the fork arms to the lower end of the post. Extending snugly between these fork arms and pivoted to the latter on a horizontal pin 13 is a lug 14 forming part of a carrier which also includes a threaded stem 15 and a relatively larger diametered stop flange 16 between this stem and the lug 14. A pen-receiving holder 17 of the usual cap-like shape has its closed end threaded upon the stem and seated on the outer face of the stop flange 16. 80

The lug 14 preferably is of circular section transverse of the axis of the pivoting pin 13, and the periphery of this lug is engaged by a friction plug 18 which slidably fits the upper portion of the bore 12 of the post. This plug is continually pressed upwardly by a compression spring 19 interposed between the bottom of the plug and the tip of a screw 20, which screw is threaded into the lower end of the bore of the post, while another and desirably stronger compression spring 21 is interposed between the head 20^A of the screw and the annular shoulder 9 of the tubular fitting. Thus arranged, the post and screw together con- 95 100

stitute a post member socketed on the supporting member.

With the parts thus assembled, the downward pressure of the spring 21 on the head 5 of the screw acts through this screw to draw the tapering lower post portion tightly into the tapering bore portion of the tubular fitting, thereby creating a frictional resistance to a rotation of the post.

10 However, the post can be rotated by a sufficient effort, or with much less effort by first lifting the post slightly against the pressure of the spring 21 so that the tapering post portion will clear the tapering bore 15 portion of the said fitting.

Owing to the action of the upper spring 19 in pressing the plug 18 against the lug 14 of the carrier which supports the pen-receiving cap 17, this plug acts after the manner 20 of a brake to hold the carrier in any inclination to which it may have been moved, and by selecting a spring 19 of suitable strength I can secure this latching of the carrier while still permitting the inclination 25 to be changed instantly and with but slight effort on the part of the user. However, by socketing a long tapering portion of the post in a correspondingly tapered portion of the supporting member and drawing the post 30 downward by a spring, I wedge the post in the supporting member so that the post will not be accidentally rotated during the pivotal movement of the pen receptacle upon the post.

35 To enhance the appearance, I desirably machine the lug 11 of the carrier so that its periphery corresponds to the spherical contour of the fork arms 11; and with the peripheral lug portion thus convexed (as shown in Fig. 40 3) I desirably concave the upper end of the friction plug or brake 18, so as to have the plug engage a considerable portion of the said lug.

To avoid a sticking of this friction plug, I 45 desirably make the same of a different material than the post and the carrier—as for example by using brass for the post and carrier, while making the friction plug of hard fibre. The tubular fitting may be of the same material—desirably brass—as the post, since the post can readily be raised slightly away from its tapering seat, particularly when the fork arms are substantially knob-shaped (as in Figs. 1 and 3) so that they can be digitally 50 grasped for this purpose.

55 With the parts thus arranged, it will be evident from Fig. 3 that all portions except the nut 6 and the base 1 can initially be assembled as a unit, and that the adjustment of the 60 spring tensions can be made before this unitary assembly is attached to the base. Consequently, the manufacturer (and even the dealer) can reduce his stock by carrying a supply of such assemblies and of the corresponding 65 nuts, together with an assortment of bases of

different styles, materials or colors, thus reducing both the required investment and the storage space. Furthermore, a mere rotational movement of the screw 20 simultaneously adjusts the tensions of both springs, so 70 that even the user can readily make this adjustment if he finds it desirable.

However, while I have heretofore described my invention in an embodiment in which both 75 springs as well as the screw are housed by the tubular fitting; in which the socketing member is in the form of a nipple, and in which one spring bears against an inner shoulder in the fitting, I do not wish to be limited to these 80 or other details thus disclosed.

Obviously, many changes might be made both in the construction, the arrangement and the materials without departing either from the spirit of my invention or from the appended claims.

85 For example, Fig. 4 shows portions of another embodiment in which the tubular fitting 22 is relatively short and has no inner shoulder, and in which the head of the screw 23 is disposed below the said fitting. In this case, 90 the spring 21 is interposed between the head of the screw and the lower end of the fitting 22.

95 Fig. 5 shows still another embodiment, namely one in which the upper bore portion 24 of the nipple or supporting member is cylindrical. In this case the post has a cylindrical shank 25 slidably fitting this cylindrical bore portion 24 and also has a flange 26 above its said shank, which shank seats on the upper end of the nipple.

100 With each of the illustrated embodiments, the upper spring 19 permits the plug 18 to move up or down to compensate for variations in the radius of the pivoting lug 14. Likewise, the spring 21 can be distorted to compensate for any lack of accurate axial alining of the screw 20 with the post. Consequently, my invention permits an instantaneous movement 105 of the pen-receiving holder to any desired position and an adequate latching of the parts in adjusted position, without requiring a high degree of accuracy in the manufacture of the parts.

110 Furthermore, while I have here shown a nipple form of the supporting or socketing member on which the post is mounted, it will be obvious that the exterior shape of this member is immaterial. Hence I do not wish to be limited in this respect, nor do I wish to 115 be limited to the conjoint employment of all novel features of my invention.

I claim as my invention:

120 1. A fountain pen stand including an upright supporting member, a post slideable and rotatable on the supporting member and formed so as to seat downwardly on the latter, spring means interposed between the post and the supporting member for urging the post to seat on the supporting member, a car-

- rier pivotally connected to the post on a horizontal axis, and separate spring means interposed between the post and the carrier for deterring movement of the carrier about its pivoting connection to the post.
2. A fountain pen stand as per claim 1, including single means for adjusting the effective pressure of both of the spring means.
3. A fountain pen stand including an upright supporting member, a post slideable and rotatable on the supporting member and formed so as to seat downwardly on the latter, spring means interposed between the post and the supporting member for urging the post to seat on the tubular member, a carrier pivotally connected to the post on a horizontal axis, and a spring-pressed brake carried by the post and engaging the carrier to deter movement of the carrier about its pivoting connection to the post.
4. A fountain pen stand as per claim 3, in which the spring-pressed brake comprises a braking member slideable on the post and a spring continuously urging the brake against the carrier.
5. A stand for fountain pens comprising a base, an upright supporting member fast upon the base, a tubular post having its lower portion socketed in the supporting member and having a forked upper end, a carrier having a portion extending between and pivoted to the arms of the forked upper end of the post, a pen receptacle mounted on the carrier, separate spring means for resisting rotation of the post, and spring means for resisting movement of the carrier with respect to the said fork arms.
6. A fountain pen stand as per claim 5, in which the two spring means include a screw threaded into the post, and two compression springs associated with the screw and respectively serving to resist movement of the post and of the carrier.
7. A desk pen stand including an upright and tubular supporting member having its upper bore portion tapering downwardly and having a downwardly facing shoulder below the lower end of the tapering bore portion; a post movable upwardly with respect to the supporting member and having a tapered part normally socketed in the said tapering bore portion, the post being forked at its upper end and having a vertical bore leading upwardly to the space between the arms of the fork; a receptacle carrier having a portion pivoted between the arms of the fork; a pen-receiving receptacle pivotally mounted on the carrier; a screw threaded upwardly into the bore of the post, and a compression spring interposed between the head of the screw and the said shoulder to resist upward movement of the post with respect to the supporting member.
8. A desk pen stand including an upright and tubular supporting member having its upper bore portion tapering downwardly; a post having a tapered part socketed in the said tapering bore portion, the post being forked at its upper end and having a vertical bore leading upwardly to the space between the arms of the fork; a receptacle carrier having a portion pivoted between the arms of the fork; a pen-receiving receptacle pivotally mounted on the carrier; a screw threaded upwardly into the bore of the post, and a compression spring interposed between the tip of the screw and the said receptacle carrier for resisting pivotal movement of the receptacle carrier with respect to the post.
9. A fountain pen stand including an upright and tubular supporting member, a post rotatably socketed in the upper portion of the supporting member, a pen-receptacle carrier pivoted upon the post, a spring interposed between the supporting member and the post for resisting rotation of the post on the supporting member, and a separate spring brake interposed between the post and the said carrier for resisting movement of the carrier about its pivoting connection to the post.
10. A fountain pen stand including an upright and tubular supporting member, a post rotatably socketed in the upper portion of the supporting member, a pen-receptacle carrier pivoted upon the post, a screw threaded upwardly into the post, a spring interposed between one portion of the screw and a portion of the supporting member for resisting rotation of the post on the supporting member, and a spring brake interposed between the carrier and another portion of the screw for resisting movement of the carrier about its pivoting connection to the post.
11. A fountain pen stand including an upright supporting member; a post member mounted on the supporting member for rotation about a vertical axis, a pen-receptacle carrier pivotally connected to the post on a horizontal pivot axis, and two springs bearing respectively against different portions of the post member; one spring being disposed for resisting rotation of the post on the supporting member, and the other spring being disposed for resisting movement of the carrier about its pivotal connection to the post.
